A. J. LAVIOLETTE.
 VISIBLE TITLE PLATE FILE FOLDER.
 APPLICATION FILED NOV. 15, 1913.

1,115,216.

Patented Oct. 27, 1914.

UNITED STATES PATENT OFFICE.

ALBERT J. LAVIOLETTE, OF NEW YORK, N. Y.

VISIBLE-TITLE-PLATE FILE-FOLDER.

1,115,216.

Specification of Letters Patent. Patented Oct. 27, 1914.

Application filed November 15, 1913. Serial No. 801,144.

To all whom it may concern:

Be it known that I, ALBERT J. LAVIOLETTE, a citizen of the United States, and a resident of the borough of Manhattan, city and State of New York, have made certain new and useful Improvements in Visible-Title-Plate File-Folders, of which the following is a specification.

My invention relates to a title plate adapted to be integral with or attached to the upper edge of the back member of a file folder or to a file guide such as is used in vertical filing systems. In files of this kind, the title is usually written upon or attached to a tab extension on the back member of the file folder, the tab being in the plane of the folder. This places the title in a vertical plane and when the file folders are close together renders it difficult to read the titles.

The object of my invention is to produce a title attachment for file folders in which the face of the plate or member, adapted to receive the name or title of the contents of the folder, shall be at an angle to the back member and substantially at right angles to the line of vision so that the titles can be readily read without fingering the folders. The prismatic construction shown and hereinafter described is preferable, for it has the added advantage of stiffening the upper edge of the back member of the folder and gives a better grip for the fingers in selecting and removing the folder from the file.

My title plate may be embodied in several ways for instance as a tab, attachable at any position along the upper edge of the back member of the folder or as a separate strip of material properly creased or scored which may be folded and secured along the entire upper edge. Such a strip may be scored, reinforced and gummed and supplied to users for attachment to the ordinary file folders or the file folder may be manufactured with an integral extension of the upper part of the back member which may be scored, reinforced and gummed but not folded and afterward secured to the back member. The advantage of leaving the folders or the title plate attachment in this form, is that they may readily be inserted in a typewriter and the name and title written upon the same, after which the material may be folded along the scores and the end pasted or otherwise secured to the back member so as to

produce the forwardly projecting prismatic construction substantially as described.

To meet the requirements of different users, my invention may be embodied in various forms, several of which are shown in the accompanying drawings.

Figure 1 is a perspective view of several file folders with my improvement; Fig. 2 represents the back member of a file folder with the scored and reinforced extension before the same is folded; Fig. 2^a is a section of the form shown in Fig. 2 when folded; Fig. 3 represents my title plate as a separate scored and reinforced strip; Fig. 4 shows the method of attaching the form of Fig. 3; Fig. 5 represents several folders with the attachable tab form of my invention and Fig. 6 shows one of the attachable tabs.

Referring to the drawings, A represents a file folder which may be folded in any desired or preferred manner to meet the requirements of the filing system to be used and may comprise the back member 1 and the front member 2 suitably hinged or folded at 3. In carrying out one form of my invention an integral extension of the upper end of the back member 1 is scored or creased at 4, 5 and 6, the scoring at 6 being on the opposite side from that of 4 and 5, so that the material will tend to take a fold or bend in the opposite direction. The outer face of the material between the scorings 4 and 5 is adapted to serve as the title plate 7 and is preferably reinforced in any suitable manner. The reinforcing strip 8 may be of the same material as the rest of the folder, but this is not necessary, and may be secured in any preferred manner as by paste or glue.

When the creased extension of the back member is folded and secured to the back member it will assume the position shown in Fig. 2^a, forming a prism or prismatic ridge below the upper edge of the back member 1 and entirely in front thereof. The object of this construction is to facilitate reading the titles and to permit the fingers to readily enter between adjoining file folders to grasp the prismatic edge of the folder it is desired to remove. The forward edge of the prism of one file folder contacts with the back member of the file folder in front of it, thus uniformly spacing them. The prismatic extension of the back member also extends over the top edge of the front member 2 so as to

conceal the contents of the folder. The front member 2 being below the prism also prevents the upper edge thereof from becoming bent over or otherwise obstructing the view 5 of the title.

In some cases it may be preferable to supply the folders with my attachment in flat form substantially as shown in Fig. 2 (or Fig. 3) in which form it may be readily inserted in a typewriter and the name, title or other matter written upon the face of the title plate. After thus writing the title on the face of the title plate 7, the material is folded over along the scoring 4 and thus 10 along 5 to bring the reinforcing strip 8 on the inside and the title face outside. The extension is further folded or bent outwardly along the score 6 and the end 9 secured to the back member 1 in such way as to form a 15 substantially equilateral, triangular prism with one face thereof serving as the title plate and the other part 10, as a brace. The triangular prismatic form together with the reinforcement of the strip 8 produces a rigid 20 construction which will retain its shape and serve as a ready means of grasping and lifting the selected folder.

As previously stated I preferably make the scored member, which when folded produces the title plate, integral with the back member of the folder. Obviously, however, it may be made as a separate piece as shown in Fig. 3 and secured to the upper edge of the back member of the folder, as indicated 25 in Fig. 4 of the drawings. In this form a narrow strip of material, preferably the same as the folder is scored at 4^a, 5^a, 6^a, just as is done when the material is integral as in Fig. 2, and a reinforcing strip 8^a secured 30 to the back or under side of the title plate 7^a. The scored strip, as with the form shown in Fig. 2, may be written upon before folding, and then may be secured to the upper edge 35 of the back member 1 of the folder with paste, glues or other suitable means so as to produce the triangular or other prismatic form projecting forward from the back member of the file folder. As indicated in Fig. 4, the back member 1^a is secured to the 40 back face of the back member 1 and the end 9^a to the front face producing substantially 45 the same prismatic construction as shown in Fig. 1 and having the same advantages.

If it should be preferable to have the title 50 plate in narrow tab form projecting above the upper edge of the back member of the file folder, then I may construct it substantially as indicated in Figs. 5 and 6. In this form I preferably use a slightly heavier or 55 thicker material both for the scored strip and for the reinforcing strip. In the form shown the ends of the strip are preferably secured together with rivets or the like just 60 below the triangular prism so as to leave a 65 considerable amount of material extending

below as an apron to serve as means for securing the tab to the back member of the folder. Ordinarily the friction between the apron of the tab and the edge of the back member will be sufficient to hold the tab in 70 place, thus permitting the tab to be readily changed from one folder to another, if desired. On the other hand, if permanency is required, the apron of the tab can be glued, riveted or otherwise secured to the 75 edge of the back member of the folder.

In carrying out my invention, it will readily be understood that various specific changes and modifications in the structures may be made without departing from the 80 spirit and scope of the accompanying claims.

I claim:

1. As a new article of manufacture a name or title plate file folder, comprising a front member and a back member, a title 85 plate member integral with said back member and at an angle thereto, a brace member at an angle to said title plate member and to said back member and a member extending from said brace member along the front 90 of and parallel to said back member and adapted to be secured thereto, thereby producing a rigid prismatic structure adapted to project above the edge of said front member. 95

2. As a new article of manufacture a name or title plate file folder, comprising a front member and a back member, a title plate member integral with said back member and at an angle thereto, a reinforcing strip secured to the back of the last named member, a brace member at an angle to said title plate member and to said back member and a member continuous with and extending from said brace member along the front of 100 and parallel to said back member and adapted to be secured thereto, thereby producing a rigid prismatic structure adapted to extend above the top edge of said front member. 105

3. As a new article of manufacture a file folder comprising a front and back member united at the bottom to form a pocket the back member of which is provided with an integral extension along the 110 upper edge thereof, the material of said extension being creased along three parallel lines so that it may be folded to form a hollow prism, the upper face of which is adapted to carry the name or title of the 115 folder contents, the end of the material beyond said creases being adapted to be secured to the back member of said folder.

4. As a new article of manufacture a file folder comprising a front and back member 120 united at the bottom to form a pocket the back member of which is provided with an integral extension along the upper edge thereof, the material being creased along three parallel lines so that it 125

130

- may be folded to form a hollow prism, the upper face of which is adapted to carry the name or title of the folder contents, the end of the material beyond said creases being 5 adapted to be secured to the back member of said folder, and a reinforcing strip secured, between the creases, on that part of said extension forming the name or title face of said prism for stiffening the same.
- 10 5. As a new article of manufacture a name or title plate file folder, comprising a front member and a back member the latter being provided with a creased extension adapted to be folded along the creases so 15 that the material extends forward at an angle to said back member then back to the back member and finally downward parallel to said back member, said last named portion being adapted to be secured to said back member, thereby producing a rigid hollow prism projecting in front of and below the 20 upper edge of said back member, and a reinforcing strip within the prism thus formed and secured thereto substantially as described.
6. As a new article of manufacture a name or title plate file folder, comprising 25 a front member and a back member the latter being provided with a creased extension adapted to be folded along the creases so that the material extends forward at an angle to said back member then back to the 30 back member and finally downward parallel to said back member, said last named portion being adapted to be secured to said back member, thereby producing a rigid hollow prism projecting in front of and below the 35 upper edge of said back member, and a reinforcing strip within the prism thus formed and secured thereto substantially as described.

In testimony whereof, I have hereunto set 40 my hand in the presence of two subscribing witnesses.

ALBERT J. LAVIOLETTE.
